UNITED STATES PATENT OFFICE.

CLARENCE K. BALDWIN, OF CHICAGO, ILLINOIS, ASSIGNOR TO ROBINS CONVEYING BELT COMPANY, A CORPORATION OF NEW JERSEY.

APPARATUS FOR QUENCHING COKE.

Application filed August 12, 1922. Serial No. 581,406.

To all whom it may concern:

Be it known that I, CLARENCE K. BALDWIN, a citizen of the United States, and resident of Chicago, in the county of Cook and State of Illinois, have invented certain new and useful Improvements in Apparatus for Quenching Coke, of which the following is a specification.

This invention relates to apparatus for quenching coke; my object being to provide an apparatus of simple and efficient construction and operation whereby hot coke, immediately after its discharge from the ovens, is rapidly and thoroughly quenched with a minimum volume of water; whereby excess moisture is eliminated from the coke, and whereby such coke, in a relatively cool and dry state, is directly delivered to a suitable conveyer.

The invention, in its preferred form of embodiment herein illustrated, comprises a rotary coke-conveying platform which is so mounted and arranged in respect to the ovens that the platform can be readily positioned to receive the coke from any predetermined oven or ovens; means for rotating the platform whereby the coke is well distributed thereon; means for subjecting the progressing coke, in a part of its path, to the influence of a quenching liquid, and means in another part of such path for discharging the then relatively cool and dry coke from the platform. Underlying the platform, adjacent the quenching zone, is a pan or trough into which the liquid drains from the coke, and overhanging the platform and its contents is a protective hood having an appropriate steam and fume outlet leading to a suitable point of discharge.

The invention also comprises novel features of construction and combinations of parts which will be hereinafter described and claimed.

In the drawings—

Figure 1 is a plan of a coke quenching apparatus embodying a preferred form of my invention; the front of the ovens being shown.

Fig. 2 is a side elevation of the apparatus, part of the hood being broken away.

Fig. 3 is a transverse vertical section through the apparatus and the discharge openings of the adjacent ovens, as on the line 3—3 of Fig. 1.

Fig. 4 is a horizontal section of the apparatus, as on the line 4—4 of Fig. 3.

Fig. 5 is a sectional detail showing the deflecting plate, and adjuncts.

Fig. 6 is a perspective view of the delivery conduit, the pivoted shelves or chutes thereof being omitted.

Referring to the drawings, 10 designates coke ovens arranged in vertical rows as usual. In front of and below the discharge openings of the ovens is arranged a suitable frame structure 11 on which the rails 12 of a track are supported.

On the rails are mounted the wheels 13 of a car which may be moved in front of any vertical row of ovens as desired. The car preferably comprises an iron frame including standards 14, and longitudinal and transverse beams 15, 16, respectively, all being suitably arranged and bolted together to provide a rigid structure of appropriate shape and size for its intended purpose. Supported on the car frame, by bars 17, for example, depending from the upper beams, is a sheet metal hood including a partial cylindric shell 18 and a roof 19. One end of the shell is located beyond the side of the car frame adjacent the ovens, and is secured, as at 20, to the adjacent vertical wall 21 of an upright trough-like conduit 22 into which the hot coke may be discharged from the ovens, as will presently appear. The other end of the shell terminates short of the opposite vertical wall of the conduit, as at 23, so as to afford an open or unconfined space above the track, as seen most clearly in Figs. 1 and 4.

The conduit is of sufficient length to extend vertically in front of any row of ovens. It is open at its upper and lower ends, its back 24 and the side wall 21 being cut away at the bottom, as at 25, to afford an open discharge space. A suitably-disposed pipe 26 connects the upper rear part of the conduit with a central stack 27 rising from a perforated cover plate 28 supported on the car frame; and a pipe 29 also connects a flaring or dome-like chamber 30 in the roof of the hood with the stack, said chamber being located directly above the quenching zone hereinafter referred to. By the pipe connections just described the fumes and hot gases from coke delivered to the conduit from the ovens, and also the steam

evolved within the hood during the quenching of the coke therein, are conducted to and discharged by way of the stack. The conduit is equipped with spaced-apart shelves 5 or chutes 31 adapted to be positioned in proximity to the bottoms of the respective ovens of any of the rows preparatory to the discharge of the coke from the ovens. In the present instance the shelves or chutes 10 are supported on horizontal rocker-bars 32 which are pivoted at their ends in the side walls of the conduit. The trunnions of the bars project beyond one side of the conduit and are equipped with crank-arms 33 which 15 are flexibly connected together and to one arm 34 of a hand lever 35 by means of chains 36, for example. The hand-lever is fulcrumed to a suitably-disposed post 37 on the framework of the car, so that by proper 20 manipulation of the lever the shelves or chutes 31 can be simultaneously rocked on their bearings to raise or lower the shelves or chutes, as desired. These shelves or chutes are raised preparatory to the moving 25 of the car along the track, thus permitting them to clear the front projections of the ovens. When the car is located with the conduit thereof in front of a row of ovens the shelves or chutes are lowered in order 30 that the contents of any oven or ovens of the row may be pushed on the shelves or chutes and directly thereby into the conduit.

A rotary coke-conveying platform is mounted and arranged to underlie the hood 35 and the conduit in such a manner as to receive the hot coke delivered into the conduit from the oven or ovens. This platform preferably comprises an outwardly and downwardly inclined annular bed 38 having a peripheral guard rim 39 and an inner up-standing cylindrical wall 40, the upper surface of the bed having a protective covering of fire brick 41 or other refractory material. The bed is secured to and supported 40 by a spider 42 fast to the foot of a central supporting shaft 43 which is mounted to rotate in suitable bearings 44 in a cylindrical supporting body 45 fixedly secured to and carried by the framework of the car. The 45 cylindrical body 45 and wall 40 are in spaced concentric relation to each other and are provided with spaced-apart annular flanges 46, 47, respectively, constituting tracks. Between these tracks are interposed 50 a series of anti-friction wheels 48, the shafts of which are preferably journaled in and between a pair of concentric rings 49 encircling the body 45. Hence the platform is uniformly supported by and freely rotatable 55 on the stationary body 45.

Surrounding the top of the wall 40 is a trough 50 adapted to contain water or other sealing liquid into which depend flanges 51, 52 formed respectively on the inner peripheral edge of the roof of the hood and

on an annular plate 53 secured to the reduced upper portion of the stationary body 45. Thus is provided a liquid seal, which serves effectively to preclude the escape of steam around the inner portion of the hood 70 roof in the region of the quenching zone. Such steam, being evolved during the quenching operation, rises through the pipe 29 to the stack, as previously mentioned.

Any suitable means for rotating the platform may be employed. In the present instance the upper end of the shaft 43 has fast thereon a worm wheel 54 with which meshes a worm 55 on a driven shaft 56 whereby the inclined annular bed can be slowly rotated in a path beneath the hot coke fed through the conduit 22, and such coke thus be well distributed on the rotating bed. The shaft 56, which has its bearings supported on the car frame, is provided at one end 80 with a bevel gear 57 in mesh with a similar gear 58 on a cross-shaft 59 which also has its bearings on the car frame. The shaft 59 is operatively geared with a motor 60 at one end of the frame, and is provided with 85 a loose sprocket wheel 61 which is connected by a sprocket chain 62 with a sprocket wheel 63 on one of the car axles. Both shafts are provided with suitable clutches 64, 65, respectively, by the operation of which the 90 shaft 56 and the sprocket wheel 61, or either of them, can be rendered active or idle as desired.

When the car, by actuation of the motor, is run along the track to a position in front 100 of a row of ovens, the clutch 65 is manipulated to unclutch the sprocket-wheel 61, and the clutch 64 is operated to establish the worm shaft connection with the motor. Thereupon the coke-conveying platform is 105 rotated counter-clockwise and the coke is delivered thereto from the adjacent oven or ovens by way of the conduit 22. Hence the falling coke is well distributed on the traveling surface of the platform. The coke thus distributed is progressively carried under the hood and immediately subjected to the quenching operation. The quenching devices preferably comprise a series of water spraying pipes 66 which are located within the 110 upper part of the hood and adjacent the conduit, and are connected to a common water supply pipe 67. Thus the coke as rapidly as it is carried from the conduit by the platform is subjected to the quenching influence 115 of the water, and by reason of the strewn condition of the coke a relatively small amount of water is required to effect the 120 uniform and thorough quenching thereof.

Preferably the platform is partially encircled by the rim of a segmental pan or trough 68 which underlies the platform and is supported by brackets 69 depending from the shell of the hood. This trough extends from the wall 21 of the conduit to a point 125 130

well in advance of the quenching zone, and is so arranged that the water directed upon and flowing from the coke is discharged over the peripheral rim of the inclined bed 5 and into the pan or trough during the travel of the distributed mass of coke in a path at and for an extended interval beyond the region of the quenching zone. In the continued progress of the coke on the platform such coke is freed from excess moisture, and is 10 finally discharged from the platform at the opening of the hood above the platform. The means for thus discharging the coke comprises preferably an angularly-disposed deflecting plate 70 which overhangs the path of the platform, said plate depending in close relation to the platform and being supported by bars 71 affixed to the framework of the car. When the progressing coke im- 15 pings against the opposing angular face of the plate such material is progressively deflected outwardly of and discharged from the platform, falling thence into the space between the rails upon which the wheels of 20 the car are mounted. Suitably arranged to run between and parallel with the rails is the upper run of a conveying belt 72 which directly receives the falling coke from the platform, and transports it to a suitable location for storage, or other purpose. 25

While I have herein shown and described in detail a preferred embodiment of my invention, it is to be understood that I do not limit myself to the particular construction 30 and mechanisms disclosed, as the same may be variously modified within the principle of the invention and the scope of the appended claims.

I claim:—

40 1. In a coke quenching apparatus, a car structure, an annular coke-conveying platform rotatably supported on said structure, a coke-delivery conduit located on and at one side of the structure and having an outlet directly overlying and spaced above the path of travel of the platform, and means for rotating said platform during the delivery of coke thereto from the conduit, whereby said coke is distributed on and trans- 45 ported by the platform.

50 2. In a coke quenching apparatus, a car structure, an annular coke-conveying platform rotatably supported on said structure, a coke delivery conduit located at one side of the structure and having an outlet overlying the path of travel of the platform, means for rotating said platform during the delivery of coke thereto from the conduit, whereby said coke is distributed on and trans- 55 ported by the platform, and means for quenching the progressing coke on the platform.

60 3. In a coke quenching apparatus, a car structure, an annular coke-conveying platform rotatably supported on said structure,

a coke delivery conduit located at one side of the structure and having an outlet overlying the path of travel of the platform, means for rotating said platform during the delivery of coke thereto from the conduit, 70 whereby said coke is distributed on and transported by the platform, means for quenching the progressing coke immediately after its deposit on the platform, and means remote from the quenching means for dis- 75 charging the quenched coke from the platform during its rotation.

4. In a coke quenching apparatus, a car structure, a coke-conveying platform includ- 80 ing an outwardly and downwardly inclined annular bed rotatably supported on said structure, a coke delivery conduit located at one side of the structure and having an outlet overhanging the path of travel of the bed, means for rotating said platform, and 85 means for quenching the coke immediately after its deposit on the platform.

5. In a coke quenching apparatus, a car structure, a coke-conveying platform rotatably supported on said structure, a coke de- 90 livery conduit located at one side of the structure and having an outlet overlying the path of travel of the platform, means for rotating said platform during the delivery of coke thereto from the conduit, whereby 95 said coke is distributed on and transported by the platform, means for quenching the progressing coke immediately after its de- 100 posit on the platform, and a water pan or trough located adjacent the periphery of the platform in the region of the quenching means.

6. In a coke quenching apparatus, a car structure, a coke-conveying platform includ- 105 ing an outwardly and downwardly inclined annular bed rotatably supported on said structure, a coke delivery conduit located at one side of the structure and having an outlet overlying the path of travel of the bed, means for rotating said platform, means 110 for quenching the progressing coke immediately after its deposit on the platform, and a water pan or trough located adjacent the periphery of the platform in the region of the quenching means. 115

7. In a coke quenching apparatus, a car structure, a coke-conveying platform rotatably mounted on said structure, a hood over- 120 hanging said platform, a conduit located at one side of the hood and adapted to de- liver coke to the platform, quenching means arranged within said hood and above the platform, a stack, a pipe leading to the stack from the hood in the region of the quenching means, a pipe leading to the stack from the conduit, and means for rotating said platform.

8. In a coke quenching apparatus, a car structure, a coke-conveying platform ro- 130 tatably mounted on said structure, a hood

overhanging said platform, a conduit located at one side of the hood and adapted to deliver coke to the platform, quenching means arranged within said hood above the platform, a stack, a pipe leading to the stack from the hood in the region of the quenching means, a pipe leading to the stack from the conduit, means for rotating said platform, and means remote from the quenching means for discharging the quenched coke from the platform.

9. In a coke quenching apparatus, a car structure, a cylindrical supporting and bearing body on said structure, a central shaft mounted in said body, a coke-conveying platform connected with and carried by said shaft, said platform having an inner upstanding cylindrical portion spaced from and concentric with the said body, anti-friction wheels between the said cylindrical portion and the cylindrical body, means for rotating said shaft, a stationary hood overhanging said platform, and coke delivery means leading to said platform.

10. In a coke quenching apparatus, a car structure, a cylindrical supporting and bearing body on said structure, a central shaft mounted in said body, a coke-conveying platform connected with and carried by said shaft, said platform having an inner upstanding cylindrical portion spaced from and concentric with the said body, anti-friction wheels between the said cylindrical portion and the cylindrical body, means for rotating said shaft, a hood overhanging said platform, a water seal device between the top of the hood and said cylindrical body, and coke delivery means leading to said platform.

11. In a coke quenching apparatus, a car comprising a wheeled structure mounted to travel on a track, a coke-conveying platform rotatably supported on said structure, a hood overhanging said platform, a coke delivery conduit located at one side of the hood adjacent the ovens and depending near to the path of travel of the upper surface of the platform, said conduit being adapted by movement of the car along the track to be positioned in front of a row of ovens, and means for rotating said platform when the conduit is thus located.

12. In a coke quenching apparatus, a car comprising a wheeled structure mounted to travel on a track, a coke-conveying platform rotatably supported on said structure, a hood overhanging said platform, a coke delivery conduit located at one side of the hood adjacent the ovens and depending near to the path of travel of the upper surface of the platform, said conduit being adapted by movement of the car along the track to be positioned in front of a row of ovens, means for rotating said platform when the conduit is thus located, and quenching means ar-

ranged within said hood above the platform.

13. In a coke quenching apparatus a car comprising a wheeled structure mounted to travel on a track, a coke-conveying platform rotatably supported on said structure, a hood overhanging said platform, a coke delivery conduit located at one side of the hood adjacent the ovens so as to overlie the path of travel of the platform, said conduit being adapted by movement of the car along the track to be positioned in front of a row of ovens, means for rotating said platform when the conduit is thus located, quenching means arranged within said hood above the platform, and means whereby the quenched coke is discharged from the platform.

14. In a coke quenching apparatus a car comprising a wheeled structure mounted to travel on a track, a coke-conveying platform rotatably supported on said structure, a hood overhanging said platform, a coke delivery conduit located at one side of the hood adjacent the ovens so as to overlie the path of travel of the platform, said conduit being adapted by movement of the car along the track to be positioned in front of a row of ovens, means for rotating said platform when the conduit is thus located, quenching means arranged within said hood above the platform, and means whereby the quenched coke is discharged from the platform.

15. In a coke quenching apparatus a car comprising a wheeled structure mounted to travel on a track, a coke-conveying platform rotatably supported on said structure, a hood overhanging said platform, a coke delivery conduit located at one side of the hood adjacent the ovens so as to overlie the path of travel of the platform, said conduit being adapted by movement of the car along the track to be positioned in front of a row of ovens, means for rotating said platform when the conduit is thus located, quenching means arranged within said hood above the platform, a conveyor extending longitudinally of the track, and means whereby the quenched coke is discharged from the platform to the conveyor.

16. In a coke quenching apparatus, a car comprising a wheeled structure mounted to travel on a track, a coke-conveying platform including a downwardly and outwardly inclined bed rotatably supported on said structure, a hood overhanging said bed, a coke delivery conduit located at one side of the hood adjacent the ovens so as to overlie the path of travel of the bed, said conduit being adapted by movement of the car along the track to be positioned in front of a row of ovens, means for rotating said platform when the conduit is thus positioned, quenching means arranged within said hood above the platform, and a water pan or trough located adjacent the periphery of the platform in the region of the quenching means.

form in the region of the quenching means.

17. The combination with a plurality of vertical rows of coke ovens, and a track extending along and below the fronts thereof, 5 of a car comprising a wheeled structure mounted to travel on said track, a coke-conveying platform rotatably supported on said structure, a hood overhanging said platform, a coke delivery conduit located at one side 10 of the hood adjacent the ovens so as to overlie the path of travel of the platform; said conduit being adapted to be positioned in front of a row of ovens, movable shelves or chutes mounted in said conduit in proximity 15 to the floors of the respective ovens of a row, means for moving said shelves or chutes toward or from the adjacent ovens, and means for rotating said platform when the conduit is positioned to receive the coke 20 from any oven or ovens of a row.

18. The combination of a car frame comprising end posts and longitudinal and transverse beams, a coke-conveying platform mounted to rotate about a vertical axis on 25 said frame, said platform including an annular bed, means for rotating said platform, a hood overhanging said bed, means for delivering coke to said bed in one part of its rotation, and an angularly disposed deflecting plate supported by said beams and depending therefrom into close relation to the 30 bed in another part of its rotation.

19. The combination of a car frame com-

prising end posts and longitudinal and transverse beams, a coke-conveying platform mounted to rotate on a vertical axis on said frame, said platform including an annular bed, means for rotating said platform, a hood overhanging said bed, means for delivering coke to said bed in one part of its 35 rotation, means for directing a quenching liquid toward the bed in another part of its rotation, and an angularly disposed deflecting plate supported by said beams and depending therefrom into close relation to the 40 bed in still another part of its rotation.

20. In a coke-quenching apparatus, a car structure, a coke-conveying platform rotatably supported on said structure, a coke delivery conduit located at one side of the 50 structure and having at its lower end a lateral outlet overhanging the platform, a hood including a shell extending from the outlet side of the conduit and partially encircling the platform, quenching means arranged within said hood adjacent the outlet side of the conduit, a stack, a pipe connection between the hood and the stack, and means for discharging the coke from the 55 platform in proximity to the opening of the 60 shell.

Signed at New York, in the county of New York and State of New York this 3rd day of August A. D. 1922.

CLARENCE K. BALDWIN.
